N. C. HAWKS, OF MILWAUKEE, WISCONSIN.

Design No. 3,743, dated November 9, 1869.

DESIGN FOR A PRINTERS' TYPE-CASE STAND.

The Schedule referred to in these Letters Patent and making part of the same.

I, N. C. HAWKS, of the city and county of Milwaukee, and State of Wisconsin, have invented and produced a new and original Design for Type-Case Stands for Printers, of which the following is a specification.

The nature of my design is for an iron type-case stand, and is fully represented in the accompanying drawings, to which reference is made.

Claim.

I claim, as my invention, the design for a type-case stand, as shown.
